(57) **CLAIM**

I claim the ornamental design for a beverage dispenser, as shown and described.

DESCRIPTION

FIG. 1 is a front perspective view of a beverage dispenser showing my new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is an enlarged front view of the display screen portion of beverage dispenser, the rest of the beverage dispenser removed for ease of illustration; and,

FIG. 9 is a sectional view along the line 9-9 of FIG. 2. The broken lines are for environmental purposes only and form no part of the claimed design.
